UNITED STATES PATENT OFFICE.

ROBERT D. BRADLEY, OF CANTON, OHIO, ASSIGNOR TO THE CANTON RUBBER COMPANY, OF CANTON, OHIO, A CORPORATION.

WATER-BOTTLE FUNNEL-NECK.

SPECIFICATION forming part of Letters Patent No. 733,899, dated July 14, 1903.

Application filed September 24, 1902. Serial No. 124,615. (No model.)

To all whom it may concern:

Be it known that I, ROBERT D. BRADLEY, a citizen of the United States, residing at Canton, in the county of Stark and State of Ohio, 5 have invented a new and useful Water-Bottle Mouth, of which the following is a specification.

The invention relates to the mouth of a rubber water-bottle or other flexible and elastic reservoir; and its object is to provide a firm and non-collapsible mouth for such bottles through which the bottle can be conveniently filled or emptied and by which it can be suspended on a hook or pin without obstructing the opening. I attain this object by the construction and arrangement illustrated in the accompanying drawings, in which—

Figure 1 is a vertical section of the mouth; 20 Fig. 2, a perspective view of the mouth, showing an eye thereon and having some parts broken away; Fig. 3, a side elevation showing the adaption of the mouth to a syringe-reservoir, and Fig. 4 a detached perspective 25 view of the inflexible cup.

Similar numerals refer to similar parts throughout the drawings.

The mouth is made on the inflexible cup 1, made of metal or other stiff material and preferably formed oval in cross-section with its sides straight. The cup is open at the top, and the bottom 3 is preferably inclined downward and inward, as a funnel, to the aperture or spout 4. The spout is closed by the screw- 35 plug 5, as illustrated, or by an ordinary cork or other suitable stopper. The external rim-flange 6 is formed at the upper edge and the external bead 7 at the bottom of the cup.

The neck 8 of the bottle is suitably shaped 40 and formed of a size to contract snugly around the sides of the inflexible cup between the rim-flange and the bottom bead, and in attaching the neck to the cup there is preferably provided the intervening base-band 9, 45 which band is glued or cemented to the sides of the cup between the rim-flange and the bottom bead and on which base-band is in turn glued or cemented the neck of the bot-

tle. The bottle-neck is then tightly wrapped with the fine wire 10, either continuously or 50 by a few wraps each above and below and in the middle, as illustrated, after which the finishing-band 11 is put in place and is glued or cemented around the bottle-neck and over the wire wrapping. The suspending-eye 12 55 is formed or attached on one side of the cup when it is desired to hang the bottle on a hook or pin, as in case of the syringe-reservoir 13.

An inflexible collar or ring has sometimes 60 been provided in the neck of a flexible bottle and the flexible material extended or projected upward and outward therefrom to form a funnel; but a funnel so formed easily collapses, and a mouth designed on this plan in 65 suitable proportions requires the neck of the bottle to be formed so small that it is quite difficult to stretch it enough to remove the bottle from the mold on which it is made, and by locating the funnel-spout and its stopper 70 in the bottom of an inflexible cup the stopper is always readily accessible for manipulation.

What I claim as my invention, and desire to secure by Letters Patent, is—

1. In combination, a flexible bottle having a neck, an inflexible cup attached by its sides in the neck, a spout leading from the bottom of the cup into the bottle, and a stopper in the spout.

2. In combination, a flexible bottle having a neck, an inflexible cup attached by its sides in the neck, and a funnel-shaped bottom in the cup having an aperture opening into the bottle.

3. In combination, a flexible bottle having a neck, an inflexible cup attached by its sides in the neck, and an aperture in the bottom of the cup opening into the bottle.

In testimony whereof I have signed my name to this specification in the presence of two subscribing witnesses.

ROBERT D. BRADLEY.
